UNITED STATES PATENT OFFICE.

FREDERICK W. RUBIN, OF INDIANAPOLIS, INDIANA.

SEALING CONSTRUCTION.

Application filed February 2, 1925. Serial No. 6,353.

To all whom it may concern:

Be it known that I, FREDERICK W. RUBIN, a citizen of the United States, and a resident of Indianapolis, county of Marion, and State of Indiana, have invented a certain new and useful Sealing Construction; and I do hereby declare that the following is a full, clear, and exact description thereof, reference being had to the accompanying drawings, in which like numerals refer to like parts.

This invention relates to a sealing construction for doors, windows and the like, and is of a character similar to that disclosed in my prior Patent No. 1,311,775, dated July 29, 1919.

The chief object of the present invention is to construct a sealing means which is not only adjustable if desired but which is likewise substantially leak proof in that it seals the joint by simultaneously contacting the two adjacent surfaces of two angularly positioned faces.

Another object of the invention is to produce an articulated sealing construction which provides a substantially continuous sealing strip, the articulation being provided for adjustability to take care of warping of one or both of the faces and their respective relative positions.

The chief feature of the invention consists in providing a supporting portion upon which is mounted, as by means of positioning in grooves, a pair of sealing strips of flexible material such as felt or the like, and which extend angularly of each other, and as herein disclosed, transversely of each other.

Another feature of the invention consists in the formation of two adjacent ends of the supporting members before mentioned, and the formation of complementary surfaces upon an intermediate hinge or joint forming bracket which is not only adapted to form an articulated construction with said adjacent supporting members, but is adapted to simultaneously position and maintain therein, the sealing means between the ends of the strips. Furthermore, the hinge bracket or joint is also adapted to clamp the sealing support to the supporting surface to which it is attached.

The full nature of the invention will be understood from the accompanying draw-

ings and the following description and claims.

In the drawings, Fig. 1 is a perspective view of a door casing and door such as is commonly employed in dry kilns with the invention applied thereto. Fig. 2 is a top plan view of one end of one of the sealing sections. Fig. 3 is an end elevational view of the section shown in Fig. 2. It is taken on line 3—3 of Fig. 2 and in the direction of the arrows. Fig. 4 is a top plan view of a pair of sections showing a joint and an intermediate clamp construction. Fig. 5 is an enlarged transverse sectional view showing the sealing strip in operative relation, and is taken in plane 5—5 of Fig. 4 in the direction of the arrows.

In the drawings 10 indicates the door casing which may be of the usual or any preferred construction and 11 indicates the door which may be mounted in any suitable manner, but generally is mounted upon rollers 75 and slides lengthwise of the door casing when being opened or closed, as is the case with structures of this class. In kilns of the character described, the doors and casings frequently warp, and such warpage 80 causes a crack or aperture between the door opening and closure, which would permit the escape of the heated air and would permit the entrance of cold air. This air transference would seriously effect not only the 85 lumber being dried, but would also be uneconomical. The present means, therefore, is designed to provide a positive seal between the door and the door casing independent of the degree of warpage therebetween. Such 90

a positive seal is secured by utilization of a multiple clamping action and a multiple contact seal in the arrangement whereby the two adjacent and angularly positioned faces of the seal are simultaneously engaged by a 95 multiple acting clamp to simultaneously seal the joint between said two warped surfaces and thus prevent the transference of air between the kiln and the outside.

Herein the sealing construction is shown 100 including a base or supporting member 12, which is shown provided with two longitudinally extending slots or grooves 13 and 14, and these slots are herein shown rectangular and are positioned upon two transversely positioned faces and are transversely

positioned also. The slot 13 carries a longitudinally extending sealing strip 15 of suitable material, such as felt or the like, which material projects outwardly from the slot 5 in which it is anchored or otherwise suitably secured and into engagement with the door 11. A similar strip 16 is similarly positioned in slot 14 and similarly projects from said slot but into engagement with the casting 10. Herein (see Figs. 4 and 5) an L-shaped clamp 17 is adapted to engage simultaneously two anchored faces of the supporting base 12 and cause the strips 15 and 16 to simultaneously engage the door 11 and the casing 10. Such clamping engagement of the supporting base is secured by a clamping member 17 being elongated as at 18, and provided with an elongated slot 19. Positioned in the slot 19 and suitably secured to the casing 10 in this instance, is a screw 20, with which is associated a washer 21, as shown. It will be readily apparent that independent of the warpage of the casing 10 and the door that if the kiln is closed, the sealing strip base 12 may be adjusted so as to simultaneously contact both of the adjacent surfaces of the door and the casing, therefor, and thus provide a sealed or substantially air tight joint therebetween.

If desired, the before mentioned sealing construction may be extended along the side of the door continuously from end to end, and in this event the base member 12 should be sufficiently resilient through its relatively long length so as to yield and thus adjustment can be made throughout the length of the joint. To positively insure such flexibility, however, an articulated construction is herein disclosed.

The aforesaid articulated construction includes a plurality of sealing strip sections, which are suitably formed at their adjacent ends and associated with said formed ends is a member which simultaneously serves as a clamp, a sealing strip positioning device and a joint. Herein the complementary formation is a tongue and groove arrangement, and herein (see Figs. 2, 3, 4 and 5) the groove is formed in the end of the base 12 and is indicated by the numeral 22. Herein the same is shown rectangular but any preferred outline may be employed. The combination clamping bracket and joint consists of a body portion 25, having a projecting ledge 26 upon its upper surface, and said projecting ledge is adapted to form a registering angular arrangement with the base 12, as shown clearly in Fig. 4. Projecting oppositely from each other and the body 25, are a pair of projections 27, which projections are each receivable by one of the notches, grooves or slots 22. Herein the body 25 is also shown with oppositely and laterally extending projections 28, which overlie the projections 27 and thus serve to

engage the outer face of the sealing strip base 12 for simultaneously anchoring said base, thereby eliminating the use of an adjacent clamp construction, previously described and indicated particularly in Figs. 4 and 5.

The under-face of the body portion 25 is herein shown provided with a registering groove 29, which groove is adapted to receive the sealing strip 16. It will be understood that the sealing strip 15 is positioned in the registering angle formed by the body portion 25 and the angular projection 26. Extending rearwardly from the before mentioned joint construction is a wing portion 30, substantially similar to the wing extension 18, previously described, and said wing 30 includes the usual elongated slot 31, with which is associated the clamping bolt 20 and washer 21. If it is desired, the supporting base may be articulated, that is, formed in sections and the sealing strip continue throughout the length of one longitudinal surface. This is the arrangement shown in Fig. 4. If, however, it is desired, the sealing strip may be severed and each supporting base be provided with its particular sections of sealing strips. In this instance the construction is formed as shown in Figs. 2 and 3. It will be readily apparent, therefore, that the clamping member shown in the bottom portion of Fig. 4 prevents leakage between joints, since it in reality includes substantially the same construction as the sealing base 12 so far as positioning the strips is concerned.

The invention claimed is:

1. The combination with a wall member and an adjacent closure member, of a sealing construction for the same including a plurality of articulated supporting bases, a joint between adjacent ends of a pair of said supporting bases, sealing means carried by said supporting bases, said joint having co-operating portions intermediate the ends of said supporting bases for engaging the end projecting portions of the sealing means and maintaining the same in sealing position.

2. The combination with a wall member and an adjacent closure member, of a sealing construction for the same including a plurality of articulated supporting bases, a joint between adjacent ends of a pair of said supporting bases, sealing means carried by said supporting bases, said joint being so formed as to provide clamping surfaces for clamping engagement with the ends.

3. The combination with a wall member and an adjacent closure member, of a sealing construction for the same including a plurality of articulated supporting bases, a joint between adjacent ends of a pair of said supporting bases, sealing means carried by said supporting bases, said joint having co-operating portions intermediate the ends

of said supporting bases for engaging the end projecting portions of the sealing means and maintaining the same in sealing position, said joint being further provided with 5 portions for engaging the ends for clamping the same into sealing position.

4. A device of the character defined by

claim 3 characterized by the addition of a complementary lateral joint between the end of the support and the clamping joint. 10

In witness whereof, I have hereunto affixed my signature.

FREDERICK W. RUBIN.
